ATTORNEY.

UNITED STATES PATENT OFFICE.

EMIL FISCHER, OF BALTIMORE, MARYLAND, ASSIGNOR TO ELLIOT,
OTTENHEIMER & ELLIOT, OF SAME PLACE.

DESIGN FOR A CIGAR-BUNCH.

SPECIFICATION forming part of Design No. 23,229, dated April 24, 1894.

Application filed November 28, 1893. Serial No. 492,303. Term of patent 14 years.

To all whom it may concern:

Be it known that I, EMIL FISCHER, a citizen
of the United States, residing at Baltimore,
in the State of Maryland, have invented and
5 produced a new and original Design for a
Cigar-Bunch, of which the following is a speci-
fication.

Figure 1 is a view of the obverse side of
the cigar bunch. Fig. 2 is a view of the other
10 or reverse side.

The leading feature of my design consists
of five cigars, *b*, *b*, *b'*, *c*, *c*, forming a broad flat
bunch, *A*, having two opposite edges which
are curved to approximate the outline of an
15 ellipse and the cigars on said broad flat sides

having the appearance of being plaited or
twisted together and exposing to the view a
part of each one of the cigars from either of
the broad sides of the bunch, and with a band,
d, around the bunch at each end. 20

I claim—

The design for a bunch of cigars as herein
shown and described.

In testimony whereof I affix my signature in
the presence of two witnesses.

EMIL FISCHER.
